Attorneys.

UNITED STATES PATENT OFFICE

PAUL SCHMIDT, OF MUNICH, GERMANY

DEVICE FOR REGULATING THE OUTPUT OF CENTRIFUGAL PUMPS

Application filed December 13, 1929, Serial No. 413,841, and in Germany June 20, 1929.

Until quite recently regulation of the output of centrifugal pumps was confined to throttling down large pump outputs, by means of sluice valves or the like, to give the 5 desired pressure or the desired quantity of water. Only just lately have attempts been made to apply a scientific form of regulation, using a type of construction known in the art of water turbine building and comprising a guide device fitted with Fink's rotatable blades.

The present invention has for its object to provide a regulating arrangement which is better suited to the peculiar properties of centrifugal pumps and which, therefore, operates to better hydraulic effect than the arrangement of this kind known hitherto. To this end, according to the invention, it is proposed to provide, for the regulation of output 20 in centrifugal pumps, devices which render it possible to vary the size of the blade surfaces of the rotor wheel in such a manner that an increase in the blade surfaces results in an increase in output while a reduction in these 25 surfaces gives a reduction in output.

The invention has particular reference to the arrangement, on the blade wheels of centrifugal pumps, of separate surface members or bodies which are kept in place, either individually or collectively, by means of positioning devices and are moved thereby upon the relatively immovable blade surfaces proper. The devices according to the invention will effect regulation in a manner which 30 is favourable from the hydraulic standpoint if, when the blade surfaces are varied, the profile of the passages remains unchanged.

The advantage of maintaining the profile of the passages constant is particularly apparent in the fact that the relative retardation which the liquid, in general, undergoes in the guide passages, takes place at all times under the optimum conditions determined by the original construction. The general advantages of the devices according to the invention reside pre-eminently in the fact that regulation of output is effected at those constructional parts of the centrifugal pumps 45 which transfer energy to the water, whereas the types of construction known heretofore

set out to regulate the output by adjusting the guide apparatus, that is to say, adjusting a device having no direct connection with the exchange of energy between pump and liquid. Thus, in accordance with the invention, the 55 size of the working surface itself determines the amount of energy to be imparted to the fluid and one can speak of a directness of regulation which is not a property of the known constructions. Consequently the devices according to the invention give better 60 hydraulic action even at a trifling technical expenditure. Predominantly the regulation of output is carried out in such a manner that the blade surfaces are increased or diminished 65 in a direction at right angles to that of the current of liquid. In this connection it appears that the profile of the passages (regarded in the direction of the flowing liquid) remains practically unchanged, so that, by 70 these means, the same conditions of flow are practically ensured throughout the whole range of adjustment. Furthermore, the new arrangement is also concerned with a variation of the blade surfaces in the direction of 75 the flowing liquid.

The accompanying drawing shows diagrammatically, in a section through the axis of the main shaft, one example of a radial pump constructed according to the invention and providing for variation of the blade surface in a direction perpendicular to the path of the fluid. The upper half of the drawing shows the output regulator in a position different from that shown in the lower 85 half.

In this constructional example the rotor wheel or impeller 1, to which fluid is admitted from both sides, is mounted in a casing 2. The rotor wheel is secured to the driving 90 shaft 4 by means of two hubs or bosses 3. The devices for varying the blade surface consist, according to the invention, of surface members or blade sections 5 which are carried by the walls or shrouds 6 of the wheel 1 and can 95 be pushed in axial direction over the blade surfaces of the said wheel. The surface members or blade sections 5 are part of the impeller blades of the pumps and each cooperates with a corresponding blade on the im- 100

steller 1 to form the active areas of the impeller blades, and thus by adjustment of the shrouds 6 in an axial direction, the active areas of the impeller blades are increased or decreased depending upon the direction of movement of the shrouds 6 to vary the output of the pump. The walls or shrouds 6 of the wheel are respectively connected each by means of ribs 7 and a hub 8 to one of a pair of sleeves 9 extending over the shaft 4. The sleeves 9 extend out of the casing 2 into the open on both sides and are held by positioning devices 10. These positioning devices 10 can be shifted in the axial direction in any convenient manner, for instance, by means of devices similar to those commonly used in turbine construction in connection with governors. The upper half of the illustration shows the rotor wheel in a position which gives the largest blade surfaces. The lower half of the figure shows an intermediate setting with smaller blade surfaces.

In cases where the variation in blade area has only to be trifling in amount, the displaceable walls 6 of the rotor wheel may be provided with grooves into which the blade surfaces of the wheel, which, relatively speaking, is fixed may be pushed to a greater or less extent.

Devices similar to those shown in the drawing can easily be arranged for pumps with diagonal flow wheels or even for axial flow pumps. In devices appropriate to these conditions, so far as concerns enlargement of the blade surfaces in the direction of flow of the fluid, the devices constitute an exact combination of the basic blade and passage profile, since the contacting and relatively displaceable surfaces run only within the path defined by the profile. For rotors with purely axial admission the rule must also be followed that the whole of the contact surface of the parts of the blade surfaces which are relatively movable is formed as a helical surface with a constant pitch.

What is claimed is:

1. In a centrifugal pump, an impeller embodying a hub, blades, and a shroud, blade sections carried by said shroud and cooperating with said blades to form the active blade surfaces of the impeller, said shroud being adjustable in an axial direction for varying the active blade areas of said impeller.

2. In a centrifugal pump, a shaft, an impeller embodying a hub keyed to said shaft, blades rigidly carried by said hub, a shroud rotatable with and movable along said shaft, and blade sections carried by said shroud and cooperating with the hub carried blades to form the active blade area of the impeller, whereby adjustment of the shroud along the shaft will vary the active blade area of the impeller.

3. In a centrifugal pump, a shaft, an impeller embodying a hub keyed to said shaft,

blades rigidly carried by said hub, a shroud rotatable with and movable along said shaft, and blade sections carried by said shroud and cooperating with the hub carried blades to form the active blade area of the impeller, whereby adjustment of the shroud along the shaft will vary the active blade area of the impeller, said blade sections conforming in shape to said blades whereby variation of the active blade surfaces may be varied without affecting the profile of the impeller passages.

4. In a centrifugal pump, a shaft, an impeller embodying a hub keyed to said shaft, blades rigidly carried by said hub, a sleeve slidably mounted on said shaft and rotatable therewith, a shroud for the impeller connected to said sleeve, and blade sections carried by said shroud and cooperating with the hub carried blade sections to form the active blade area of the pump whereby adjustment of the sleeve will vary the active blade area of the impeller.

In testimony whereof I have signed my name to this specification.

PAUL SCHMIDT.
